UNITED STATES PATENT OFFICE

CHARLES C. PLUMB, OF PROVIDENCE, RHODE ISLAND

APPARATUS FOR TRANSMITTING HEAT

Application filed August 10, 1928. Serial No. 298,744.

This invention relates to apparatus for transmitting heat from a heating medium to an object or material to be heated, the general object of the invention being to provide 5 a closed container in which is placed mineral salts, with means for heating the container to bring the salts to a molten state, said container having a coil therein and means for passing a non-coking oil through the coil 10 and conveying the oil from the coil to the object or through the material to be heated whereby the object or material will be heated to a high degree.

This invention also consists in certain 15 other features of construction and in the combination and arrangement of the several parts, to be hereinafter fully described, illustrated in the accompanying drawing and specifically pointed out in the appended 20 claim.

In describing the invention in detail, reference will be had to the accompanying drawing which is a diagrammatic view, partly in 25 section, showing the invention in use for heating material in a tank.

In the drawing, the numeral 1 indicates a closed container in which the mineral salts, indicated by the numeral 2, are placed, and in which is also arranged a coil 3, the lower 30 part of which is immersed in the salts and a tank 4 forms an extension of one end of the container and contains a non-coking oil, as indicated by the numeral 5. The coil is provided with an extension 6 at one end which 35 extends into the tank 5 to a point adjacent the bottom thereof. The other end of the coil is connected by a pipe 7 with a pump 8 which is driven from any suitable source 40 through the belt and pulleys, shown generally at 9. An air pump 10 is also driven from the shafting which is connected with the pump 8 and suitable clutch means 11 are provided for connecting each pump with the power means. The outlet of the pump 8 is 45 connected by the pipes 12 and 12' with a coil 13 which may be placed in the tank 14 of a tank car containing asphalt, though it will, of course, be understood that the invention 50 may be used for heating any other material besides asphalt or it may be used for heating

any desired object. The outlet of the coil 13 is connected by the pipes 15 with the top of the tank 5.

Thus it will be seen that when the pump 8 is in operation, oil will be drawn from the bottom of the tank 5 through the coil 3 and pipe 7 and forced through the pipes 12 and 12' into the coil 13 and then the coil will return to the tank 5 through the pipes 15.

Burners 16 are placed under the container 1 and the tank 5 and pipes 17 connect these burners with a tank 18 which contains a supply of liquid fuel. An air tank 19 is placed over the tank 18 and pipes 20 connect the air tank with the air pump 10, a branch pipe 21 connecting one of the pipes 20 with the tank 18 so that the liquid fuel in said tank 18 is held under pressure. The tank 19 is connected by the pipes 22 with the discharge line 12 and 12' of the pump, so that the compressed air in the tank 19 can be used for forcing the oil from the coil 13 back into the tank 5 after the heating operation has been completed.

A by-pass line 23 connects the pipe 12 with 75 one of the pipes 15 so that the oil can be circulated through the coil 3 and the tank 5 while it is being heated to the proper degree before passing it through the coil 13. It will, of course, be understood that suitable valves, 80 such as shown at 24, are placed in the pipe lines to properly control the flow of oil and air through the system, and safety valves 25 and pressure gauges 26 are also provided 85 wherever necessary or desired. Pyrometers or other suitable temperature indicating devices may also be placed wherever desired.

From the foregoing it will be seen that the heat from the burners will heat the salts in the container 1 and the oil in the tank 5. 90 The heat will melt the salts so that they assume a liquid state and as the coil 3 is partly immersed in the liquid salts, the oil in the coil will be highly heated and the valve 24 in the by-pass 23 is opened and those in the pipes 12 and 15 closed so that the pump 8 will draw the oil through the coil 3 and force it through the by-pass 23 back into the tank 5 and the oil is thus circulated until it reaches 95 the proper temperature. Then the valve in 100

the by-pass is closed and the valves in the pipes 12 and 15 opened so that the highly heated oil will pass through the coil 13 and return to the tank 5 through the pipes 15, and this circulation of the oil through the coil 13 is continued until the material in the tank 14 is heated to a sufficient degree. Of course, during this operation, the air pump furnishes compressed air into the fuel tank 18 so that fuel is supplied to the burners and after the operation has been completed, the valves are manipulated so that compressed air from the tank 19 can be forced through the coil 13 to force the air therefrom back into the tank 5.

With this invention, a uniformity of control of the heat transmitted is secured and it enables oils to be heated at temperatures close to their flash and fire points, as the use of the liquid salts assures a very close regulation of the temperature, whereas any other method of heating the oil involves a dangerous condition because of the lack of uniform introduction of heat to the coil containing the oil.

As will be seen, the mineral salts are used as the primary heating medium, and the non-coking oil as a secondary heating medium.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

An apparatus of the class described comprising a container partly filled with mineral salts, a tank containing oil, means for heating the container and tank, a coil in the container and partly immersed in the liquid, one end of the coil extending into the tank to a point adjacent the bottom thereof, a pump connected with the other end of the coil for drawing the oil from the tank through the coil to the point of use and a return pipe for returning the oil to the tank.

In testimony whereof I affix my signature.

CHARLES C. PLUMB.
